United States Patent Office

Des. 212,367
Patented Oct. 8, 1968

212,367

BIRD FEEDER

Norman G. Carlson, P.O. Box 8571,
White Bear Lake, Minn. 55110

Filed Dec. 29, 1967, Ser. No. 9,994

Term of patent 14 years

(Cl. D30—14)

FIG. 1 is a right front perspective view of a bird feeder, showing my new design.

FIG. 2 is a top plan view thereof.

FIG. 3 is a bottom view; and

FIG. 4 is a back view.

The left side is a mirror image of the right side.

I claim:

The ornamental design for a bird feeder, as shown and described.
